UNITED STATES PATENT OFFICE.

WILLIAM B. MUNN, OF MEMPHIS, TENNESSEE, ASSIGNOR OF ONE-HALF TO MAY SCHARFF, OF MEMPHIS, TENNESSEE.

WRAPPING-MACHINE.

1,340,665.

Specification of Letters Patent. Patented May 18, 1920.

Application filed December 10, 1918. Serial No. 266,114.

To all whom it may concern:

Be it known that I, WILLIAM B. MUNN, a citizen of the United States of America, residing at Memphis, in the county of Shelby 5 and State of Tennessee, have invented certain new and useful Improvements in Wrapping-Machines, of which the following is a specification.

The present invention relates to an improved wrapping machine, designed particularly for use in wrapping or packaging collars and cuffs in the laundry, but adaptable of course for use in other connections and for other purposes, as will readily be understood. For convenience of description, however, the invention in the present instance will be referred to as a collar and cuff packaging or wrapping machine, preferably operated manually, and designed to build up a uniformly cylindrical bundle or package of laundered cuffs or collars, having the ends of the paper wrapper tucked in at both ends of the package, and presenting a neat and attractive bundle as to its shape and appearance.

The invention consists essentially in the utilization of a fixed receptacle having a movable bottom upon which the collars to be wrapped are placed, and in certain novel combinations and arrangements of parts whereby the size of the paper sheet required is gaged, and particularly in combining with the movable bottom of the receptacle, means for imparting friction whereby the bottom is free to be pulled up, but must be pushed downwardly, all as will hereinafter appear more specifically.

In the accompanying drawings one complete example of the physical embodiment of the invention is illustrated, constructed and arranged according to the best mode so far devised for the practical application of the principles of the invention.

In the drawings:—

Figure 1 is a perspective view showing the machine complete, and illustrating also in connection therewith a paper cutter and a tagging or labeling device for the completed package.

Fig. 2 is a side view of the machine. Fig. 3 is an enlarged view, in section, showing details of construction of the receptacle.

ceptacle, its movable bottom, and the lifting and lowering means for the bottom.

Fig. 4 is a top plan view of the parts in Fig. 3.

Fig. 5 is a sectional view taken at line 5—5 of Fig. 3.

Fig. 6 is an edge view showing the friction device for retarding the downward movement of the plunger rod that supports the movable bottom or plunger head. Fig. 7 is a side view, as seen from the right in Fig. 6.

Fig. 8 is a vertical sectional view of the friction device or retarder.

Fig. 9 is a top view of the device as in Fig. 7.

In the preferred embodiment of the invention as illustrated in the drawings, the machine is adapted for manual operation and is depicted as supported upon a table 1 in combination with the frame 2 which supports the paper roll 3 from which the wrapping paper for the bundle is to be taken.

The paper from the roll passes over guide rolls 3' and is cut by a reciprocable cutter 4 slideable on the guide rod 5 and provided with a rotary cutting knife 6 that travels in the groove 7 of the fixed bar 8 supported in the frame 2. The sheet of wrapping paper is drawn from the roll 3, by hand, and the required length of paper is cut from the roll by manual manipulation of the slideable cutter, and then this sheet of cut paper is wrapped about the receptacle 9 in which the collars and cuffs are piled or stored preliminary to wrapping them.

The receptacle is preferably of metal, cylindrical in shape to conform to the collars, and of suitable dimensions to receive the collars in their normal condition, as indicated by dotted lines in Fig. 2, wherein the paper wrapper is also indicated by dotted lines.

The receptacle 9 has an open top to receive the collars and cuffs, but is fashioned with a closed bottom 10, except for the central orifice 11 therein, and by means of the flange 12, exterior of the receptacle and forming an extension of the bottom, the receptacle is rigidly fixed over an opening in the table top as shown in Fig. 3.

Within the receptacle the vertically reciprocable plunger rod or stem 13, and its head being mounted and secured to the metal

14, which forms the movable bottom of the receptacle, are operable, the bottom fitting neatly within the interior of the cylindrical receptacle, and the stem 13 passing freely, 5 but not too loosely through the opening 11 in the bottom plate 10 of the receptacle. The movement of the stem and bottom is guided and rendered stable by the utilization of three vertical guide rods 15 that are 10 connected at their lower ends beneath the table top 1, by the spider frame 16, and a threaded extension bar 17 of the stem also is fixed at the center of the spider, clamping nuts 18 being provided to make a firm joint. 15 These three rods and the spider form a guide frame that is completed by the upper flanged ring 19 which surrounds the receptacle above the table and to which the rods are rigidly fastened as seen in Fig. 3. From 20 this description it will readily be seen that the stem, spider, guide rods, and ring 19 form a movable guide frame for the bottom 14 of the receptacle, and as the rods pass through small openings 20 in the bottom plate 10 of the receptacle the stability of the frame is enhanced so that these parts may 25 be lifted or depressed without wobbling. Usually the movable bottom is manipulated manually by grasping the ring 19 in the hand, and thus the bottom may be freely 30 lifted through the co-action of the frame, but preferably the lowering movement of the bottom is to be retarded, and as a matter of fact, the movement is stopped, and the 35 movable bottom held in position by means of a friction device co-acting with the stem, so that the bottom may not be lowered without power being applied, preferably by hand on the ring 19, as will be described.

40 In connection with the movable ring 19, a paper or wrapper retaining device is utilized, which includes a pair of parallel rollers 21 movable in a vertical plane with the ring 19, and supported from the ring by an 45 arm 22 pivoted at 23 in the ears 24 on the ring and a spring 25, between lugs of the arm and the ring, holds the rollers 21 against the paper that is wrapped about the receptacle. Thus the paper sheet is cut from the roll 50 and wrapped about the receptacle, the size of the sheet being determined by the eye of the operator. It will be noted that, in their fixed relation, the bottom 14 is above the ring 19, so that when the bottom edge of the 55 paper sheet is brought down to the ring 19 and the sheet wrapped about the receptacle, the upper edge of the sheet projects above the upper edge of the receptacle, and the lower edge of the sheet is below the bottom 60 of the package that is to be formed on the movable bottom, thus providing upper and lower edges of the wrapper that may be tucked in when the bundle is complete.

The retarding or friction device for the 65 stem is located just beneath the bottom plate

of the receptacle in an opening in the table top, and comprises a housing 26 preferably of cast metal in U-shape, in which are located the two friction blocks 27 and 28. These blocks lie parallel with the stem 13 70 diametrically opposite each other and have leather facing strips 29 at their inner faces frictionally engaging the stem 13. The friction block 28 is held in adjusted and fixed relation with the stem by a set screw 75 30 which bears against the block and is threaded in the housing, but the friction block 27 is designed to grip the stem, or be released therefrom, the former action for the purpose of retarding downward movement of the stem or actual holding of the stem, and the latter condition to permit the lifting, by free motion, of the stem and movable bottom. To this end the block 27 has a cam notch 31 cut in its outer edge, and within the cam notch a roller 32 is located, a light spring 27' being used for holding the block 27 against the roller 32 to hold the stem from dropping, but permit the stem to be moved or pushed down by hand pressure on the ring 19.

The housing 26 is suspended beneath the table top by its brackets 33 that are pivoted at 34 to the bracket arms 35 of the bottom plate of the receptacle, and a spring 17' 95 coiled about the stem acts as a cushion against the bottom of the housing when the bottom 14 is lifted.

On the stem 36 in Fig. 1 a spool 37 may be retained to provide convenient cord for 100 tying the completed bundle, and at 38 in Fig. 1 a paper tape holder for gummed tape is indicated for customary use.

Claims—

1. The combination with a fixed vertically 105 disposed cylinder adapted to have a sheet wrapped thereabout, of a movable bottom within the cylinder and means connected therewith for reciprocating the bottom, and said means including a member spaced a 110 predetermined distance from the bottom to form a tucking-in edge as described.

2. The combination with a vertical, cylindrical receptacle adapted to have a sheet wrapped thereabout, of a movable bottom 115 within the receptacle and means connected therewith for reciprocating the bottom, means for retarding the downward movement of said bottom, and the first mentioned means including a spaced member below the 120 bottom to form a tucking-in edge as described.

3. The combination with a fixed vertical, cylindrical receptacle adapted to have a sheet wrapped thereabout, of a movable 125 bottom within the receptacle adapted for free upward movement, and means for frictionally retarding the downward movement of the bottom.

4. The combination with a fixed receptacle 130

- adapted to have a sheet wrapped thereabout and provided with a bottom plate, of a movable bottom in the receptacle having a stem passing through an opening in said plate, a frame connected with the stem outside the receptacle, and said frame including a ring surrounding the receptacle and spaced below the bottom to act as a guide for providing a "tucking-in" edge.
- 5 10 5. The combination with a fixed receptacle adapted to have a sheet of paper wrapped thereabout with its ends overlapping, of a movable bottom within the receptacle adapted for free upward movement and adapted 15 for retarded downward movement, means for accomplishing this upward and downward movement of the bottom and said means including a member outside the recep-
- tacle, and a resilient wrapper retaining device carried by said means for engaging the overlapping edge of the wrapper.
6. The combination with a fixed receptacle adapted to have a sheet wrapped thereabout and provided with a bottom plate, of a movable bottom in the receptacle having a stem 25 passing through an opening in said plate, a frame connected with the stem outside the receptacle, a ring included in the frame surrounding the receptacle and spaced a predetermined distance below the movable 30 bottom, said stem being capable of free upward movement, and means for retarding the downward movement of the stem and movable bottom.

In testimony whereof I affix my signature. 35
WILLIAM B. MUNN.
